UNITED STATES PATENT OFFICE.

JAY G. HOYT, OF GENEVA, ILLINOIS, ASSIGNOR TO THE W. H. HOWELL COMPANY, OF SAME PLACE.

DESIGN FOR A SLEEVE-IRON.

SPECIFICATION forming part of Design No. 27,206, dated June 15, 1897.

Application filed March 20, 1897. Serial No. 628,537. Term of patent 14 years.

To all whom it may concern:

Be it known that I, JAY G. HOYT, a citizen of the United States, residing in Geneva, in the county of Kane and State of Illinois, have 5 invented and produced a new and original Design in Sleeve-Irons, of which the following is a specification.

In said drawings, Figure 1 is a perspective of a device embodying my design. Fig. 2 is 10 a side elevation, and Fig. 3 a plan, of the same; and Figs. 4 and 5 are sections on the lines 4 4 and 5 5, respectively, of Fig. 5.

The leading feature of my design consists 15 in a sleeve-iron having an elongated toe portion, a body portion, and a raised cross-bar upon the top of the body portion.

In said drawings, A represents the toe or sharpened front portion, and B the body or rear portion, of the iron. The top C of the latter is recessed at D, and within the recess 20 is the raised cross-bar or loop E. Upon the top there are also L-shaped projections F at the points indicated.

I claim—

The design for a sleeve-iron herein shown 25 and described.

JAY G. HOYT.
